UNITED STATES PATENT OFFICE

ANTHONY E. PIEKENBROCK, OF DUBUQUE, IOWA, ASSIGNOR TO E. B. PIEKENBROCK & SONS COMPANY, OF DUBUQUE, IOWA, A CORPORATION OF IOWA

SHOE

Application filed February 24, 1930. Serial No. 430,876.

This invention relates to improvements in shoes and more particularly to a shoe having a resilient longitudinal arch support secured to the upper surface of the insole adjacent the inner margin of the shoe. The present invention is an improvement in the construction shown in my co-pending application, Serial No. 426,559, filed February 7, 1930.

10 The object of the invention is to provide a shoe with a longitudinal arch support made of resilient material such as sponge rubber or pneumatically inflated rubber.

Another object is to so construct the arch support that it will efficiently support the highest part of the arch of the foot, that is, the part adjacent the inner margin of the foot; and that it will not spread outwardly or alter the general contour of its bearing 20 surface when pressure is applied to the arch support.

In the drawings:—

Fig. 1 is a top plan view of an insole and leather covering therefor, having secured to 25 the top of the insole an arch support embodying my invention, the leather cover being broken away to show the arch support.

Fig. 2 is a transverse vertical section of a shoe embodying my invention, the same being taken on the plane indicated by the dotted lines 2—2 of Fig. 1.

Fig. 3 is a view similar to Fig. 2, showing a modified form of arch support.

Fig. 4 is a side elevation of an insole and arch support embodying my invention, as the same appear when looking toward the inner side margin.

In that embodiment of my invention shown in the drawings, 10 indicates a conventional outer sole of a shoe, 11 the leather uppers, 12 the lining for the uppers, 13 a conventional inner sole, 14 the welt, and 15 a leather covering for the insole. These parts are secured together in a manner well known in shoe construction.

Between the inner sole 13 and outer sole 10, extending longitudinally of the shoe adjacent the margin at the outer side of the shoe is a substantially rigid arch support, 50 preferably in the form of a metal plate 16

secured to the under side of the insole 13. The space between the inner and outer soles not occupied by the rigid arch support 16 is filled with filling material 17.

Adjacent the inner margin of the insole, 55 and extending longitudinally of the shoe, and under the arch of the foot, is a resilient arch support 18 preferably made of sponge rubber. It is cemented to the inner sole 13 and is highest directly under the arch of 60 the foot adjacent the inner margin, as indicated by the numeral 19 on Fig. 1. From this point the arch gradually slopes downwardly toward the median portion of the shoe and toward the toe and heel sections. 65

The parts thus far referred to provide a combination stiff and flexible arch for a shoe, and are fully shown and described in my co-pending application, Serial No. 426, 559, filed February 7, 1930.

One of the novel features of improvement 70 upon the structure shown in said application consists of a side support for the flexible arch which will now be described.

A relatively thin, stiff piece of material 75 20 having a substantially straight lower margin for contacting with the top surface of the edge 21 of the insole, and having a curved upper margin 22 tapering downwardly at each end toward the lower margin, is cemented to the side of the arch support 18. The outer side 23 of the arch support 18 and the relatively stiff side support 20 are concave longitudinally and are inclined downwardly and inwardly from their top margins toward their line of connection to the insole adjacent the inner margins of the shoe. 85

After the side support has been cemented to the resilient arch support, the latter is cemented to the upper surface of the insole 90 and thereafter the leather covering 15 may be placed over the arch and insole. Without the side member 20 for supporting the overhanging, inclined side surface 23 of the arch support 18, said arch support would be 95 apt to yield unduly under pressure and would be forced downwardly and outwardly to such an extent that considerable of its supporting quality for the highest part of the arch of the foot might be lost. With 100

the side support 20 first secured to the resilient arch 18 in the manner shown, the highest portion of the arch of the foot is well supported and the tendency to displace the resilient material toward the outer margin of the inner side of the shoe is avoided. This construction holds the top surface of the arch support as intended, with its highest portion adjacent the margin and gradually sloping toward the toe, heel and side.

Although the addition of a side support 20 is a detail of construction, it is a valuable improvement in the preparation of a shoe having a resilient arch secured to the inside 15 of the shoe above the insole.

In Fig. 3, a modified form of resilient arch has been shown. It comprises a flexible casting 24 preferably made of rubber pneumatically inflated. Its shape is similar to the 20 arch support 18 made of sponge rubber and it is also provided with a relatively stiff side support 20 such as described in connection with Figs. 1 and 2.

Obviously, changes in details of construction 25 may be made without departing from the scope of my invention, and I do not intend to be limited to the precise form shown and described, except as pointed out in the appended claims.

30 I claim:—

1. In a shoe comprising an insole, outer sole and uppers secured together, a resilient arch support secured to the upper surface of the insole, extending longitudinally of 35 the sole under the arch of the foot adjacent the margin of the inner side of the shoe, the outer side surface of said arch support being concave longitudinally and inclined downwardly from its top margin toward the insole, a side member made of relatively stiff material, shaped complementary to the side surface of said support and cemented to said support, and a leather cover extending over the top and sides of the insole, the arch support and side support for the arch.

2. A shoe comprising an outer sole, an inner sole, leather uppers, an arch support made of sponge rubber located on the inner sole adjacent its outer margin along the inner longitudinal side of the inner sole, a 50 relatively stiff upright member secured to the sponge rubber support along its concave outer side surface, and a cover extending over the top of the inner sole and arch support and downwardly adjacent the relatively stiff member, between the inner sole and the uppers of the shoe.

In testimony that I, claim the foregoing as my invention, I affix my signature, this 60 21st day of February, 1930.

ANTHONY E. PIEKENBROCK.
